UNITED STATES PATENT OFFICE.

DANIEL A. LOESER, OF WALLINGFORD, CONNECTICUT, ASSIGNOR TO THE
R. WALLACE & SONS MANUFACTURING COMPANY, OF SAME PLACE.

DESIGN FOR METALLIC BORDER.

SPECIFICATION forming part of Design No. 28,469, dated April 12, 1898.

Application filed March 7, 1898. Serial No. 673,017. Term of patent 7 years.

To all whom it may concern:

Be it known that I, DANIEL A. LOESER, of Wallingford, in the county of New Haven and State of Connecticut, have invented a new Design for Metallic Border; and I do hereby declare the following, when taken in connection with the accompanying drawing and the letters of reference marked thereon, to be a full, clear, and exact description of the same, and 10 which said drawing constitutes part of this specification and represents a face view of a section of a border-strip embodying my design.

This invention relates to a design for a metallic border such as is used in the ornamentation of metal articles; and it consists of an ornamental strip, as herein described, and shown in the accompanying illustration.

As herein shown, the design consists of a border representing leaves A and flowers B 20 of the lily of the valley, the blossoms and leaves being intertwined to form a conventionalized border, as shown in the accompanying illustration.

Having fully described my invention, what 25 I claim as new, and desire to secure by Letters Patent, is—

A design for ornamental metallic border as herein shown and described.

In testimony whereof I have signed this 30 specification in the presence of two subscribing witnesses.

DANIEL A. LOESER.
